UNITED STATES PATENT OFFICE

113,676

DESIGN FOR AN EYE BANDAGE

Francis B. Mastin, New York, N. Y.

Application November 19, 1938, Serial No. 81,242

Term of patent 14 years

To all whom it may concern:

Be it known that I, Francis B. Mastin, a citizen of the United States, residing at New York, in the county of New York and State of New York, have invented a new, original, and ornamental Design for an Eye Bandage, of which the following is a specification, reference being had to the accompanying drawing, forming part thereof.

The drawing shows a perspective view of an eye bandage, showing my new design, both sides of the eye bandage being the same.

I claim:

The ornamental design for an eye bandage, as shown and described.

FRANCIS B. MASTIN.
